UNITED STATES PATENT OFFICE.

LOUIS STOCKSTROM, OF ST. LOUIS, MISSOURI.

GASOLINE-STOVE.

SPECIFICATION forming part of Letters Patent No. 350,087, dated September 28, 1886.

Application filed June 10, 1885. Serial No. 168,262. (No model.)

To all whom it may concern.

Be it known that I, LOUIS STOCKSTROM, of the city of St. Louis, in the State of Missouri, have invented a certain new and useful Improvement in Gasoline-Stoves, of which the following is a full, clear, and exact description, reference being had to the accompanying drawings, forming part of this specification, and in which—

10 Figure 1 is a side elevation of my improved stove. Fig. 2 is a vertical section through the pump and valves. Fig. 3 is a section of the pump-piston. Fig. 4 is a section of the valve closing the filling-opening. Fig. 5 is an elevation of the same open. Fig. 6 is a top view of the valve-operating lever used with the pump. Fig. 7 is a modification showing a bellows that may be used instead of the pump. Fig. 8 is a top view of the same. Fig. 9 is a 20 modification illustrating how my invention may be used with an ordinary blow-pipe, which cannot be used without opening the valve. Figs. 10 and 11 are modifications showing how the valve J may be opened automatically when the lever of the bellows is raised. Figs. 1, 7, 8, 10, and 11 are views on about the same scale. Figs. 2, 6, and 9 are views on a larger scale. Figs. 3, 4, and 5 are views on a still larger scale.

30 My invention relates to that class of gasoline-stoves having an oil-reservoir located beneath the burner, and a pump for forcing air into the reservoir to cause the flow of oil to the burners.

35 My invention consists in features of novelty hereinafter fully described, and pointed out in the claims.

Referring to the drawings, A represents the body of the stove having a table A, and B the burners, both of which may be of any ordinary construction.

C represents a reservoir for holding oil, located near the bottom of the stove, or at least beneath the burners.

40 D represents the cylinder of a pump for forcing air into the reservoir to cause the flow of oil to the burners.

D' is the piston of the pump, and D'' a hollow piston-rod, on the upper end of which is

50 a handle, D³.

The piston is preferably composed of a disk, D⁴, having an internally screw-threaded pro-

jection, D⁵, on top to receive the rod and an externally screw-threaded projection, D⁶, at bottom to receive a disk, D⁷, and a cap, D⁸. 55 Between the disks D⁴ and D⁷ is held a cup-leather, D⁹, that forms a tight fit between the piston and cylinder. The disk D⁴ has an opening, D¹⁰, with a seat, D¹¹, against which a valve D¹², is held by a spring, D¹³, between it and the 60 cap D⁸, which has an opening, D¹⁴, to receive the stem of the valve and to permit the passage of air when the valve is opened by the upward movement of the piston, the air being supplied preferably through the hollow rod 65 entering through a hole, D¹⁵. When the piston is raised, the valve opens downward, automatically compressing the spring, and as soon as the upward movement of the piston ceases the spring closes the valve, so that the air which has 70 entered the cylinder is forced by the downward movement of the piston through a pipe, I, into the oil-reservoir C, where it is held by valves J and L. The valve J is located in a casting, J', between the pump and the pipe I, into which it 75 screws. (See Fig. 2.) It extends up above the table of the stove, and on its upper end is a lever, J², that, when the valve is closed, crosses the handle D³ of the pump (see Fig. 6) to prevent the pump being worked without first turning 80 the lever from over the handle and thereby opening the valve. (See Fig. 2.) When the pump has been worked, the lever may be turned automatically over the handle by a spring, J³, on the stem of the valve. The table of the stove 85 is preferably provided with a cup, A', to receive the handle when in its lowest position. The valve L is located in a barrel, L', inserted in the pipe I, and it preferably consists of a flat hollow piece of rubber or other suitable material, with a slit, L², to permit the passage of air through it when the pump is worked. While the air is passing through the valve is 90 expanded into a tube; but as soon as the pump is stopped the valve collapses and prevents 95 the return of the air, thus affording additional security to the valve J against the escape of air from the reservoir.

In Fig. 7 is shown a bellows for compressing the air instead of the pump, and the valve J is a barrel-valve with a handle, J⁶, that has to be turned from across the lever that operates the bellows before the bellows can be worked. (See Fig. 8.) With this arrange-

ment the valve J may be opened automatically when the lever is raised by reversing the action of the spring J³ and having it act to open the valve instead of close it. The valve 5 is held closed by a projection, J¹, on the stem of the bellows, against which the handle J⁶ bears, and as soon as the bellows-lever is raised the spring turns the handle and valve, opening the latter, which remains open while 10 the bellows is being worked, as the lever is not lowered far enough to bring the projection J¹ against the handle of the valve, and when the bellows is stopped the projection moves the handle around, closing the valve.

15 N represents the oil-pipes leading from the reservoir to the burners. The reservoir is preferably filled through a short pipe, O, entering it a short distance below the top, so that it (the reservoir) cannot be entirely filled 20 with oil, leaving a space above the oil for the compressed air. The pipe is closed by a valve, P, secured to a stem, P', by a pin, P², fitting in a circumferential groove, P³, in the stem, thus permitting the stem to turn without turn- 25 ing the valve and without wearing out its packing P⁴ on the seat. The stem screws through a yoke, P⁵, hinged to the pipe at P⁶, so that the valve when opened to fill the reservoir can be turned over out of the way, as 30 shown in Fig. 5, and when it is turned back it is stopped in a vertical position by lugs P⁷ thereon coming against lugs P⁸ on the outside of the valve-seat.

Instead of a pipe being used to connect the 35 pump to the reservoir, an air-passage of any kind could be used—as, for instance, in a casting.

I claim as my invention—

1. The combination, with a gasoline-stove having an oil-reservoir, of an air-compressor 40 communicating with the reservoir, and a valve located between the compressor and reservoir having a lever or arm which in its normal position stands in the path of the compressor, rendering the compressor inoperative until 4 the valve is opened, substantially as set forth.

2. The combination, with the reservoir of a gasoline-stove, of a compressor for forcing air into said reservoir, connection between the compressor and reservoir, a valve located in 50 said connection, and which in its closed position prevents the pump from being operated, and mechanism for closing said valve automatically when the compressor has been operated.

3. The combination, with the oil-reservoir of a gasoline-stove, of an air-compressing device having a pipe leading to the reservoir and a valve located in the pipe having a lever or arm extending in normal position over the 60 compressing device, preventing access to the latter until the valve is opened by shifting the lever or arm, substantially as set forth.

4. The combination, with an oil-reservoir of a gasoline-stove, of an air-pump having a 65 pipe leading to the reservoir, a valve located between the pump and reservoir having a rod, J, closing-spring, and an arm or lever extending in normal position over the pump, rendering the latter inoperative until the arm or lever is shifted to open the valve, substantially as set forth.

LOUIS STOCKSTROM.
